UNITED STATES PATENT OFFICE

ALLAN R. KINGSTON, OF SOMERVILLE, MASSACHUSETTS

PUTLOG

Application filed March 10, 1927. Serial No. 174,186.

This invention relates to putlogs such as are employed as part of temporary scaffolding that is erected for use in working upon brick or masonry walls.

5 It is an object of the invention to produce a putlog having the required strength and durability, yet simple in structure and easily manipulated.

It is a further object of this invention to 10 provide, as a new article of manufacture, a putlog anchor attachment which can, with ease and at the expenditure of little labor, be quickly applied to a log or beam to complete the putlog. Up to the present time it 15 has been common practice for manufacturers of scaffolding apparatus to produce the putlogs complete, including the usual wooden log or beam, and to ship these complete logs to the purchasers. Naturally the freight 20 and other expense of shipping complete logs from the factory to the purchaser is comparatively great. My invention provides a putlog anchor attachment which can be manufactured, sold and shipped to the purchaser, 25 separately the purchaser furnishing the wooden logs or beams himself and applying the attachment thereto. In this way my invention obviates the expense of shipping comparatively large and heavy wooden logs 30 or beams and, therefore, the ultimate cost to the user or purchaser of the attachment is less than heretofore.

To these ends I have provided an improved putlog, and also, as a new article of manufacture, a putlog anchor attachment having the peculiar features of construction and arrangement of parts set forth in the following description, the novel features of the invention being particularly pointed out and 40 defined in the claims at the close of the description.

In the accompanying drawings:

Figure 1 is a side elevation of a putlog having my new anchor attachment applied thereto, said putlog being shown as applied to the wall of a building and to a scaffold.

Figure 2 is a section on line 2-2 of Fig. 1.

Figure 3 is an end view of the putlog, viz., the end thereof to which the anchor attachment is applied.

Figure 4 illustrates the manner in which the anchor of the putlog is inserted into, or removed from, the wall of a building.

Figures 5, 6, 7 and 8 are details of parts of the anchor attachment hereinafter described.

Having reference to the drawing, 1 represents the wooden log or joist constituting the body of my improved putlog. At one end of the body log 1 is a transversely disposed metal bar 2 bearing against that end of the log and disposed between said end and another metal bar 3 to which latter it is secured by a rivet 4. The two bars 2 and 3 are disposed crosswise, or at right angles, and permanently fastened together by the rivet 4.

The metal bar 2 is made at one end with an integral perpendicular extension 5 fitting against one side of the log 1, and at its free end this extension 5 is made with a pair of laterally projecting teeth 6 adapted to be embedded in the side of the log 1. At its opposite inner end the metal bar 2 is made with a perpendicular extension 7 that projects through a slot 8, Figs. 2 and 8, formed in the bar 3. This extension 8 is provided at its free end with a tooth or prong 9 making of said extension 7 a hook to engage the brick 19 on which said extension rests when the putlog is applied to a wall, said prong serving to hold the extension against movement away from the wall. Adjacent the bar 2 the extension or arm 7 is recessed or notched upon its lower edge as at 10. When inserting the extension or arm 7 into the brick work of the wall, or withdrawing the same therefrom, the putlog is usually canted more or less as shown in Fig. 4, and the purpose of the notch 10 is to prevent the lower edge of the extension 7 from breaking down, or chipping, the corner 11 of the brick 19 immediately beneath the extension 7.

At its opposite ends the metal bar 3 is made with integral perpendicular extensions 12, 12 fitting against, and extending longitudinally of, the top and bottom sides of the log 1. Near their extremities the extensions or arms 12 of the bar 3 are apertured to receive a bolt 13 that extends through the log 1 and, by means of which, the extensions or arms 12

are rigidly and strongly secured to the end portion of the log, said bolt 13 being provided at its threaded end with a nut 14. It will thus be seen that the metal bar 3 with its laterally extending arms 12 constitutes a vertically disposed yoke or stirrup embracing the end portion of the log 1 vertically and rigidly fastened thereto by means of the bolt 13 and nut 14. It will also be clear that through its engagement with the extension or arm 7 the yoke 3—12 rigidly holds said extension 7 against vertical displacement relatively to the log 1, and holds the end cross-bar 2 against twisting or breaking under the strain of loads imposed upon the putlog.

Near its free or inner end the arm or extension 5 of the cross-bar 2 is apertured to receive a bolt 15 provided with a nut 16, said bolt and nut serving to securely clamp the arm 5 in position against the side of the log 1 and to embed the prongs 6 in the log. Thus the arm 5 co-operates with the yoke or stirrup 3—12 in holding the arm or extension 7 and cross-bar 2 rigidly in position against displacement relatively to the log.

From the above description it will be clear that it is only necessary to drill or bore the two holes 17 and 18 for the bolts 13 and 15, respectively, to adapt the log 1 to receive the metal anchor attachment, and it will also be clear that these holes are readily located by applying the attachment to the end of the log 1 and then drilling through the apertures of arms 5 and 12.

The above described putlog anchor attachment is of inexpensive and efficient construction and can be easily and quickly applied to a log or joist by an unskilled workman. Also this anchor attachment can be shipped separately by the manufacturer thereof to users of putlogs who can make use of their own lumber in providing the log to which the attachment is applied, thus saving the expense of shipping bulky and heavy logs with the attachment.

The vertical disposition of the end embracing yoke 3—12 is advantageous for the reason that both arms 12 assist in supporting the log 1 and the stress or strain on the intermediate portion 3 is in a direction lengthwise of the latter, the upper end of the slot 8 preferably fitting against the top of the extension or arm 7 and the bottom edge of the latter bearing against the top of the brick 19 on which it rests.

As usual, the outer end of the putlog 1 may be supported by a ledger board 20 secured to posts 21 resting at their lower ends upon the ground.

The arms 5 and 12 provide a socket or cage at the outer end of the anchor hook or arm 7 within which is received the end of the putlog, said end being fastened within said cage by means of the bolts 13 and 15, one disposed vertically and the other horizontally.

It will be observed that the face of the metal member or strap 12, bears against the outer face of the wall when the scaffolding is in working position as shown in Fig. 1 and its lower corner bears thereagainst during the act of inserting or removing the brick engaging extension 7, but as the face of such strap is of substantial width and its lower wall engaging corner is rounded, it will be seen that such a good wide bearing is afforded that no injury or defacement of the outer face of the wall from contact of the putlog therewith will happen even in more or less careless handling. The close bearing of the putlog on both sides of the brick as shown in Fig. 1 is important to prevent any such loose connection with the wall as to permit longitudinal movement of the putlog from wind and other forces acting upon the scaffolding and tending to move the same.

What I claim is:

1. A putlog including a body log and an anchor attachment, said anchor attachment comprising a wall engaging member having an inner hooked end portion adapted to be inserted between two bricks of a wall and to rest upon and interlock with the brick beneath it, a relatively perpendicular integral intermediate portion to fit flatwise against the end of said body log and an outer end portion integral with and perpendicular to said intermediate portion to fit flatwise against the side of the body log; a yoke member connected with said wall engaging member having its intermediate portion fitting against the intermediate portion of said wall engaging member at right angles thereto and with its arms disposed to fit against the top and bottom sides, respectively, of the body log, and means for fastening the outer end portion of the wall engaging member and the arms of the yoke to the body log.

2. A putlog anchor attachment constructed in accordance with claim 1 and wherein the intermediate portion of the yoke is formed with an aperture through which said wall engaging member extends with its upper edge in abutting engagement with said intermediate portion of the yoke.

3. An improved putlog comprising a wooden body log and a metal end anchor, said anchor comprising a wall engaging member having a hooked end portion constituting an extension of the body log adapted to be inserted between two bricks of a wall and to rest upon and interlock with the brick beneath it, a relatively perpendicular integral intermediate portion fitting flatwise against the end of the body log, and an outer end portion integral with said intermediate portion fitting flatwise against the side of the body log and formed near its free end with a bolt receiving aperture; a yoke member having its intermediate portion connected to and in abutting engagement with said wall engaging member,

and having its arms formed with bolt receiving apertures and fitting against the top and bottom sides, respectively, of said body log, and bolts extending through the body log and through the bolt receiving apertures of the wall engaging member and yoke to fasten the anchor to the body log.

4. A putlog including a wooden body log and an anchor attachment which comprises a wall-engaging element adapted to be inserted between two bricks of a wall, and to rest upon the brick beneath it, said wall-engaging element extending longitudinally of the log and lying against the adjacent surface thereof and means securing together said element and said log, comprising metal parts which respectively engage the top and bottom surfaces of said body log and a bolt passing vertically through a hole in the body log and through said parts, the bolt having a head to engage the outer side of one part and a nut to engage the outer side of the other part.

5. A putlog including a wooden body log and an anchor attachment which comprises a well-engaging element adapted to be inserted between two bricks of a wall, and to rest upon the brick beneath it, said wall-engaging element extending longitudinally of the log and lying against the adjacent surface thereof and means securing together said element and said log, comprising metal parts which respectively engage the top and bottom surfaces of said body log and a bolt passing vertically through a hole in the body log and through said parts, the bolt having a head to engage the outer side of one part and a nut to engage the outer side of the other part, the portion of said wall-engaging element that engages the body log being at the side thereof and a bolt passing transversely through the same and through the body log.

6. A putlog including a wooden body log and an anchor attachment which comprises a wall-engaging element adapted to be inserted between two bricks of a wall, and to rest upon the brick beneath it, said wall-engaging element extending longitudinally of the log and lying against the adjacent surface thereof and means securing together said element and said log, comprising metal parts which respectively engage the top and bottom surfaces of said body log and a bolt passing vertically through a hole in the body log and through said parts, the bolt having a head to engage the outer side of one part and a nut to engage the outer side of the other part, and a connection between said log and the portion of the wall-engaging element extending longitudinally thereof.

7. A putlog anchor attachment comprising a metal wall-engaging member with two portions offset to occupy different vertical planes, one of such portions being adapted to be inserted between two bricks of a wall and the other portion adapted to extend longitudinal-

ly of a body log, said offset portions being connected by a laterally extending part integral therewith and a strap on the outer side of said integral portion with means to bear against an adjacent body log surface, and means to connect said anchor attachment with a body log.

8. A putlog anchor attachment comprising a metal wall-engaging member adapted to be inserted between two bricks of a wall and means for attaching said member to a putlog comprising a strap with opposite portions that extend parallel with one another and engage opposite sides of the putlog and a strap extending parallel with said portions and lying between them that engages another side of the putlog, said straps being attached to said wall-engaging member and having means for attachment to the putlog.

9. A putlog including a wooden body log that is rectangular in cross section with flat surfaces and an anchor attachment comprising a metal wall-engaging member adapted to be inserted between two bricks of a wall and means attaching said member to said body log comprising a strap with opposite portions that extend parallel with one another and are flat and engage opposite flat surfaces of the body log and a strap extending parallel with said opposite portions of the first-mentioned strap and lying between them and being flat and lying against another flat surface of said body log, said straps being joined to said wall-engaging member, and means including holes through the straps and elements passing through such holes and through the body log attaching them to the log.

Signed by me at Boston, county of Suffolk and State of Massachusetts, this 7th day of March, 1927.
